WASHING, RINSING, AND DRYING
APPARATUSJoseph White, Philadelphia, Pa., assignor to Mary
K. Cassidy, Philadelphia, Pa.

Application May 11, 1939, Serial No. 273,081

1 Claim. (Cl. 68—193)

This invention relates to washers and driers, and its general object is to provide an apparatus primarily designed for domestic purposes, that is capable of use for washing, rinsing and drying apparel and other fabric articles, as well as dishes and the like, in a thorough and expeditious manner, without possibility of damaging the same, in that the apparatus is based upon a thermal circulatory principle, that is the washing solution such as soapy water is heated within the apparatus and caused to circulate for travel through and about the articles, thus removing all dirt and foreign matter therefrom, without the use of agitators, suction cups and other moving elements now generally employed in washing machines.

A further object is to provide an apparatus of the character set forth, in which the different kinds of articles can be separated in groups, one above the other, and the articles can remain within the apparatus during the entire process of washing, rinsing and drying the same, so that when removed, they are in a clean, dry and sanitary condition.

Another object is to provide an apparatus that is simple in construction, inexpensive to manufacture, and extremely efficient in use and service. This invention also consists in certain other features of construction and in the combination and arrangement of the several parts, to be hereinafter fully described, illustrated in the accompanying drawings and specifically pointed out in the appended claim.

In describing the invention in detail, reference will be had to the accompanying drawings wherein like characters denote like or corresponding parts throughout the several views, and in which:

Figure 1 is a vertical sectional view taken through the apparatus which forms the subject matter of the present invention, and illustrates the manner of applying heat to bring about the circulation of the washing solution, the direction of travel thereof being indicated by the arrows.

Figure 2 is a top plan view of the apparatus.

Figure 3 is a sectional view taken approximately on line 3—3 of Figure 1, looking in the direction of the arrows.

Figure 4 is a sectional view taken approximately on line 4—4 of Figure 1, looking in the direction of the arrows.

Figure 5 is a fragmentary vertical sectional view, illustrating the application of one of the drying units which forms a part of the apparatus.

Figure 6 is a vertical sectional view, illustrating the manner of applying a hose, to bring about the rinsing of the articles after the latter have been washed.

Figure 7 is a fragmentary sectional view, illustrating the application of another type of drying unit which likewise forms a part of the apparatus.

Figure 8 is a fragmentary top plan view of the unit as shown in Figure 7.

Figure 9 is a perspective view of the article receiving and supporting rack.

Figure 10 is a detail perspective view of an insert used during the process of washing the articles and illustrates a part in section.

Referring to the drawings in detail, the reference numeral 1 indicates the body of my apparatus, and which in the form as shown is a cylindrical container provided with a bottom wall 2 and an open top, the latter being closed by a flanged cover or lid 3 provided with a central opening having an interiorly threaded upstanding annular flange 4 about the edge thereof to threadedly receive a handled cap 5, as well as for mounting a drying unit which will be later described. The cover 3 is likewise provided with a laterally disposed opening 6 closed by a cover plate 7 mounted for pivotal slideable movement and provided with a knob-like handle.

Secured to and depending from the flange of the cover 3 are hanger brackets 8 having right angle bent lower ends which have riveted or otherwise secured thereto a perforated partition plate 9 disposed slightly below the cover for cooperation therewith to provide a chamber 10 for receiving the incoming washing solution. While the plate 9 is shown as being flat, it may be of slightly convexed formation and acts as a spreading means 30 for the solution.

Mounted on the bottom wall 2 is a base plate 11 having secured thereto a strip 12 disposed in spiral formation from adjacent the center of the plate 11 to the outer edge thereof to provide a circuitous path for the heated water or washing solution to direct the same accordingly to the inlet end of a pipe line 13 providing a by-pass for the passage of the solution from the chamber 14 to the chamber 10, as the inlet end of the pipe line 13 communicates with the latter chamber, as clearly shown in Figure 1. Removably mounted within the container is what I term a basin element which includes a disk plate 15 supported upon the strip 12 for cooperation with the base plate 11 to provide the chamber 14 and the disk plate 15 has a centrally disposed opening therein, about the edge of which is formed the small end of a funnel member 16, the latter provided with an annular flange 17 about the upper margin thereof, as best shown in Figure 10 for receiving and supporting a perforated plate 18.

The plate 18 is removable and is preferably used during the washing process, and mounted upon the plate 18 or the annular flange 17 of the basin element in the event the plate 18 is removed, is a rack, which is best shown in Figure 9, for the purpose of receiving and supporting the articles to be washed, such as wearing apparel, dishes or the like, and the rack is preferably 60

of a height to extend from the basin element to adjacent the partition plate 9, as best shown in Figure 1.

The rack as shown, is made from strands of wire to provide uprights 19 having their upper ends bent at right angles upon themselves to provide horizontal handle portions 20 disposed in crossed association and secured accordingly. Fixed to the uprights at equi-distantly spaced intervals are superimposed tiers or shelves 21, each including a ring member 22 having secured thereto in bridging relation therewith strands 23 arranged in serpentine formation and in pairs, with the waves of the strands of each pair being directed outwardly from each other thence inwardly throughout the length of the strands, as clearly shown in Figure 9. It will be obvious that the tiers or shelves are for receiving or supporting the articles to be washed, rinsed and dried, and the arrangement of the strands or rods 23 will tend to facilitate the washing process of fabric articles such as apparel and the like. The provision of the shelves likewise makes it possible to separate different kinds of articles, for example delicate articles of apparel may be placed upon the upper shelf while heavy articles may be placed upon the lowermost shelf.

In Figures 5 and 7 I have illustrated two types of drying units, and the type of Figure 5 includes a circular casing 24 having an open lower end and being exteriorly threaded to be threadedly mounted in the annular flange 4 of the cover 3, so that the open lower end is in direct communication with the interior of the container. The upper end of the casing 24 is closed and the circular wall is provided with inlet openings. Suitably secured within the casing 24 is a motor driven fan 25 arranged for directing currents of air therefrom within the container, for the obvious purpose of drying articles on the shelves of the rack.

The container is provided with an outlet spout 26 in the vertical wall thereof adjacent to its lower end, and the spout is threaded for receiving a serrated cap 27 during the washing process. However, the spout 26 is also for the purpose of receiving the other drying unit of my apparatus and which includes a tubular shank 27 terminating at its outer end in an annular flange which has mounted thereon a coupling nut 28 for securing the unit to the outlet spout 26, as shown in Figure 7. The shank 27 is formed on the hollow body 29 of the unit, the body being shaped to taper outwardly from the shank in substantially turtle back formation and includes a bottom wall 30 having a heat inlet opening 31 therein of a size to allow for the free passage of heat within the unit from a source of heat, such as a burner 32, and the shank contains suitable filtering material 33 such as a steel wool cartridge to prevent passage of the flames from the burner, carbon, etc., to the container.

In order to facilitate the introduction of water within the container, I provide a hose 34, one end of which has secured thereto a socket member 35 for attachment to a spigot, as shown in Figure 6, and the opposite end has a reinforcing collar 36 thereon, with spring fingers 37 formed on the collar, and rising from diametrically opposite sides thereof, for holding the outlet end of the hose within the opening 6, the spring fingers being looped to provide seats for that purpose, as clearly shown in Figure 6. The shape

of the spring fingers likewise provide cam means for urging the fingers toward each other, when placing the hose within the opening, and it will be obvious that when the fingers are manually pressed together the hose can be readily moved 5 therefrom.

In Figure 1, it will be noted that my apparatus is suitably supported with respect to a burner 38 for heating the washing solution within the container, and while it is believed that the operation of the apparatus will be obvious from the foregoing description and disclosure in the drawings, it might be mentioned that when the apparatus is used for washing articles, the container is filled with washing solution, such as 10 soapy water, to a height to cover the top shelf of the rack. The parts are all assembled, as shown in Figure 1, and as the water becomes heated, it will follow the circuitous path provided by the strip 12 and be directed through the pipe 13 to 15 the chamber 10 for passage through the perforations of the plate 9 and thence through and about the articles upon the shelves. The water passes through the perforations of the plate 18, then is directed by the funnel member 16 to the center 20 of the chamber 14 where it is again heated, with the result it will be seen that the circulation continues until the washing process is completed. 25

After the articles have been washed, the washing solution is moved from the container by the 30 outlet spout 26, and the articles are rinsed by the application of the hose to the spigot and within the opening 6, as shown in Figure 6, and after the rinsing process has been completed, the articles are dried by either of the units shown 35 in Figures 5 and 8.

It is thought from the foregoing description that the advantages and novel features of the invention will be readily apparent.

It is to be understood that changes may be 40 made in the construction and in the combination and arrangement of the several parts, provided that such changes fall within the scope of the appended claim.

What I claim is:

In a washing apparatus, a container having an open upper end, a removable flanged closure for said end, hanger brackets secured to and depending from the flange of the closure, flat 50 perforated means secured to the brackets for disposal within the container in spaced relation to the closure to provide an upper chamber, a base plate mounted in the bottom of the container, a spirally arranged strip secured to the base plate, a removable basin element including a disk plate resting upon the spirally arranged strip to provide a lower chamber, said disk plate having a central opening therein for the passage of liquid from the container within the lower chamber to be heated, a funnel shaped member formed on said disk plate and rising from about said opening in outwardly flared formation, an outwardly directed marginal flange formed on the upper end of the funnel shaped member, a 55 perforated plate resting upon said marginal flange, by-pass means between said chambers for the passage of the heated liquid from the lower chamber to the upper chamber, and said spirally arranged strip being disposed for directing the liquid in a horizontal circuitous path from said 60 central opening to the by-pass means.

JOSEPH WHITE.
